SMOKER'S APPLIANCE

George F. Weiher, Dayton, Ohio

Application March 26, 1938, Serial No. 198,276

3 Claims. (Cl. 131—213)

This invention relates to an appliance for smokers and particularly to a tobacco smoking pipe.

An object of my invention is to provide a tobacco smoking pipe with a novel and improved stem structure which is of light weight, constructed and arranged to increase the path of flow of smoke from the pipe bowl to the pipe mouthpiece to thereby cleanse and cool the smoke prior to its entering the mouth of the smoker.

Another object of my invention is to provide an improved stem structure for a tobacco smoking pipe which has a back and forth flow therethrough constructed at least in part of relatively flat wide and long passages formed between the wall of the pipe stem and an elongated reed-like element disposed therein for spreading the smoke over and in direct contact with a large area of the pipe stem so as to produce rapid and effective dissipation of heat from the smoke to thereby insure complete cooling thereof before being drawn into the mouth of the smoker.

A further object of my invention is to provide a stem structure for a tobacco smoking pipe having the features of the preceding objects incorporated therein and which has wells or pits formed in the reed-like pipe stem insert to effect condensation of nicotine and other condensable constituents from the smoke while at the same time providing cavities for receiving the condensable constituents.

A still further and more specific object of my invention is to provide a stem construction for a tobacco smoking pipe of the type set forth in the foregoing objects which can be readily disassembled to permit thorough cleansing and clearing of collected nicotine and other sediments when necessary.

Still further objects and advantages reside in details of construction of my improved smoking pipe and in novel combinations and arrangements of parts thereof as will more fully appear in the course of the following description.

In the drawing:

Fig. 1 is a top plan view of a smoking pipe having a stem structure constructed in accordance with my invention incorporated therein;

Fig. 2 is an enlarged sectional view of the pipe shown in Fig. 1 and is taken on the line 2—2 thereof;

Fig. 3 is a sectional view of the pipe stem structure taken on the line 3—3 of Fig. 2;

Fig. 4 is a plan view of the smoke passage forming insert element of the pipe stem; and

Fig. 5 is a sectional view taken on the line 5—5

of Fig. 2 showing the portion of the element which permits communication between the passages formed thereby in the pipe stem structure.

Referring to the drawing, for illustrating my invention, I have shown in Fig. 1 thereof a tobacco smoking pipe comprising a tobacco burning bowl 10 and an integral stem portion 11. The integral parts 10 and 11 of the pipe may be formed of processed briar or any other suitable molded or machined material. A mouthpiece 12 10 preferably formed of molded hard rubber, or the like, material and provided with a central passage is threaded or fitted upon an elongated reed-like element, generally represented by the reference character 14 (see Fig. 2), which is inserted 15 in an elongated opening or chamber 15 hollowed out of the pipe stem 11. The element 14 located within the stem structure of the pipe may be formed of any suitable material such as hard rubber but is herein disclosed as being formed 20 of aluminum. Aluminum is preferred because it is of light weight, a good conductor of heat, is easily machined and lends itself to a sanitary appearance. This reed-like element 14 includes 25 spaced apart inner and outer plug ends 16 and 17 the round wall surface of which fits tightly against the wall of chamber or opening 15 in the pipe stem 11 to provide means for blocking the 30 flow of smoke therearound. A threaded portion 18 projecting outwardly from the outer plug end 17 of elongated element 14 receives an enlarged portion 19 of the centrally bored mouthpiece 12. An integral tapered portion 21 of the inner plug end 16 of element 14 extends a short distance 35 into the tobacco bowl 10 of the pipe. An elongated wall portion 22 intermediate the plug ends 16 and 17 of element 14 is machined to provide 40 flat surfaces 23 and 24 thereon which are spaced from the chamber wall 15 of pipe stem 11. The width of wall 22 is equal to the diameter of the 45 round plug ends 16 and 17 of element 14, and the sides of this elongated wall part 22 are rounded so as to also engage with a slip fit the chamber wall 15 to thereby divide the spaces formed between the flat surfaces 23 and 24 and the chamber wall 15 into two separate passages.

The elongated insert element 14 is provided with a plurality of bores which with the passages located between its flat faces 23 and 24 and the chamber wall 15 in the pipe stem 11 form an 50 extended path of flow for smoke passing from the tobacco bowl 10 to the mouthpiece 12 of the pipe. This extended tortuous path of flow of smoke is in the form of a sinuous passage for a purpose to be hereinafter more fully described. 55

A round hole 26 bored, drilled or otherwise formed in the central part of the element 14 extends from the tapered portion 21 of plug end 16 through the elongated flat or reed part 22 thereof to a point adjacent the inner shoulder of plug end 17. A pair of spaced apart small holes 27 are drilled through the tapered portion 21 of plug end 16 of element 14 and communicate with the bore or hole 26 therein. The forward end of bore or hole 26 and the holes 27 communicate with the interior of tobacco bowl 10 of the pipe. An opening or hole 28 extends from bore 26 through the wall portion 22 of element 14 and communicates with the space or passage located between the top flat face 23 of element 14 and the chamber wall 15 in stem 11. A notch 29 provided in each of the side walls of the flat wall part 22 of element 14 adjacent plug end 16 thereof (see Fig. 5) places the passage located between the bottom flat face 23 of wall part 22 of element 14 and the wall of chamber 15 in stem 11 in communication with the upper passage. An angularly disposed bore or hole 31 extends from the inner shoulder of round plug end 17 on element 14 to a centrally located hole 32 provided in the threaded projection 18 thereof. Thus, the hole 31 communicates with the space located between the lower flat face 23 of wall part 22 on element 14 and the wall of chamber 15 in the pipe stem 11 and with hole 32 which communicates with the central bore provided in the mouthpiece 12. The smoke from burning tobacco in pipe bowl 10 travels through the open end of bore or hole 26 and simultaneously through the pair of holes 27, thence toward the pipe mouthpiece 12 through bore or hole 26 to the opening 28 in the wall portion 22 of element 14. The smoke enters the upper space or passage located between the wall 22 of element 14 and the chamber wall 15 in the pipe stem, and its direction of flow is reversed to cause same to travel toward the pipe bowl 10. Upon reaching the plug end 16 of element 14, the smoke passes downwardly through the notches 29 and into the lower space or passage located between the wall part 22 of element 14 and the chamber wall 15 in pipe stem 11. Thus, the smoke again has its direction of flow reversed and now travels to the hole 31 through which it flows into hole 32 and through the passage provided in the mouth piece 12 of the pipe. By this unique arrangement the path of flow of smoke is materially increased by element 14 to provide a sinuous or tortuous smoke passage which is of at least two-thirds greater length than can be obtained from the conventional straight smoke passage in a pipe stem of equal length to the stem of the pipe disclosed.

By referring to Fig. 3 of the drawing, it will be noted that the separate passages formed between each flat face 23 and 24 of elongated wall part 22 of element 14 and the wall of chamber 15 in the pipe stem 11 is relatively flat and wide. These flat, wide and long smoke passages are an important feature in the present pipe stem structure because the passages serve to spread the smoke over and into direct heat exchange contact with an increased area of the pipe stem 11 to thereby more rapidly and effectively cause the heat of the smoke to be dissipated through the stem 11 to the atmosphere surrounding same. Since side walls of the elongated reed-like wall part 22 of element 14 contact the chamber wall 15 in pipe stem 11 and since the element 14 is formed of aluminum or any other good heat conducting material, heat absorbed thereby from the

smoke is rapidly transferred to stem 11 and dissipated from the pipe. This improved method of dissipating heat from the smoke results in a smooth, dry and cool smoke which eliminates tongue bite and raw mouth of the smoker.

My improved structure is constructed to, in addition to cooling the smoke, effectively condense nicotine and other condensable constituents of the smoke therefrom during its passage through the tortuous or artificially prolonged labyrinthine passage. For this purpose I provide in the flat faces 23 and 24 of the elongated reed-like wall part 22 of element 14 a series or a plurality of rows of substantially semicircular cavities 35. The depressions or cavities 35 form pits or wells within the long relatively flat wide smoke passages and thereby materially increase the area or wall surface of these passages to prolong flow of smoke therethrough. These wells or pits 35 cause nicotine and other condensable constituents in the smoke to be condensed therefrom during its prolonged flow lengthwise in one direction along the face 23 and in the opposite direction along the face 24 of element 14. The nicotine and other condensable substance condensed out of the smoke may accumulate or be collected in the wells or pits 35 without danger of blocking the flow of smoke in the flat wide smoke passages since these wells or pits increase the area of the passages.

The pipe mouthpiece 12 and the elongated reed-like condenser or filter element 14 are threaded to one another and the element 14 is slip fitted within the opening 15 of the pipe stem 11. Therefore, the element 14 is readily removable from pipe stem 11 for cleaning and clearing same of nicotine deposits by rotating and pulling outwardly on the pipe mouthpiece 12. The easy removal of element 14 permits the pipe stem structure to be readily disassembled and cleaned when necessary. The condenser or filter element 14 and the flat wide smoke passages formed thereby prevent slugs, flakes and juices from entering the smoker's mouth. The element 14 adds no appreciable weight to the pipe structure, is easily machined or readily cast and provides with the stem of the pipe a novel and improved pipe stem construction.

It will be apparent from the foregoing that I have provided an improved smoking pipe having a novel stem construction which produces a filtered, cool smoke free of nicotine, juices, slugs or flakes. These features, while combining to protect the smoker from a biting tongue, raw mouth and the ill effects of nicotine and other products resulting from the burning of tobacco and inhalation of its smoke, also contribute to produce a pleasing smoke and to improve the taste of any tobacco. The pipe stem construction described is of a simplified structure, can be manufactured at low cost, and the elongated reed-like insert element thereof while not increasing the weight of the pipe is of a permanent nature. By increasing the area of certain parts of the tortuous or sinuous smoke passage, I have created an artificially prolonged labyrinthine travel of the smoke from the tobacco bowl to the mouthpiece of the pipe, and this feature together with the structure of the filter or insert element of the pipe stem construction condenses substantially all of the condensable constituents from the smoke before the smoke can enter the smoker's mouth.

While the form of embodiment of the invention as herein disclosed, constitutes a preferred

form, it is to be understood that other forms might be adopted, all coming within the scope of the claims which follow.

What is claimed is as follows:

- 5 1. A smoking pipe comprising a tobacco bowl having an integral relatively long stem of small diameter extending therefrom, said stem being provided with a cylindrical chamber, an elongated insert element removably located in said 10 chamber, a mouthpiece separate from and detachably secured to said insert element and having an opening extending therethrough, said removable insert element including widely spaced apart plug-like inner and outer end portions 15 tightly fitted in continuous circumferential contact with the wall of the end portions of said chamber to block flow of smoke between said plug-like portions and the wall of said chamber, said insert element also including an intermediate 20 portion extending longitudinally between said plug-like portions thereof and provided with two flat walls spaced from the chamber wall, said intermediate portion also being provided with semicircular walls at the sides of said flat walls contacting the chamber wall substantially throughout the length of said intermediate portion of 25 said element, the flat walls and the semicircular walls cooperating with the pipe stem to form two elongated smoke passages unobstructed 30 throughout the entire distance between said plug-like portions and being in direct heat exchange relation with said stem, the outer plug-like end portion having a hole extending between the outer end of one of said smoke passages and the opening in said mouthpiece, the inner plug-like end portion and said intermediate portion of said insert element being provided with a straight continuous 35 longitudinal bore which at one end communicates with the interior of said bowl and has a communication at its other end with the outer end of the other of said smoke passages, said 40 intermediate portion of said insert element having notches formed therein adjacent the inner plug-like end portion thereof and extending from one flat wall to the other to provide communication between the two elongated smoke passages.
2. A smoking pipe comprising a tobacco bowl having an integral relatively long stem of small 45 diameter extending therefrom, said stem being provided with a cylindrical chamber, an elongated insert element removably located in said chamber, a mouthpiece separate from and detachably secured to said insert element and having an opening extending therethrough, said removable insert element including widely spaced apart plug-like inner and outer end portions 50 tightly fitted in continuous circumferential contact with the wall of the end portions of said chamber to block flow of smoke between said plug-like portions and the wall of said chamber, said insert element also including an intermediate portion extending longitudinally between said plug-like portions thereof and provided with two walls spaced from the chamber wall, said intermediate portion also being provided with semicircular walls at the sides of said 55 flat walls thereof contacting the chamber wall substantially throughout the length of said intermediate portion of said element, the said two walls and the semicircular walls cooperating with the pipe stem to form two elongated smoke passages of relatively flat wide cross-sectional contour between the stem and said intermediate portion of said element, the flat wide smoke passages being unobstructed throughout the entire distance between said plug-like portions and being in direct heat exchange relation with said stem, the outer plug-like end portion having a hole extending between the outer end of one of said smoke passages and the opening in said mouthpiece, the inner plug-like end portion and said intermediate portion of said insert element being provided with a straight continuous central 60 longitudinal bore which at one end communicates with the interior of said bowl and has a communication at its other end with the outer end of the other of said smoke passages, at least one of said semicircular walls of said intermediate 65 portion of said insert element having a notch formed therein adjacent the inner plug-like end portion thereof and extending from one of said two walls to the other to provide communication between the two elongated smoke passages, and at least one of said two walls of said insert element having depressions therein to increase the wall area of a smoke passage and to receive 70 deposits of condensable smoke constituents.
